UNITED STATES PATENT OFFICE.

WALTER P. MURPHY, OF CHICAGO, ILLINOIS.

VERTICALLY-CORRUGATED SHEET-METAL CAR END.

1,301,487.

Specification of Letters Patent. Patented Apr. 22, 1919.

Original application filed November 8, 1913, Serial No. 799,968. Divided and this application filed June 5, 1916. Serial No. 101,622.

To all whom it may concern:

Be it known that I, WALTER P. MURPHY, a citizen of the United States, residing at Chicago, in the county of Cook and State of Illinois, have invented certain new and useful Improvements in Vertically-Corrugated Sheet-Metal Car Ends, of which the following as a specification.

The invention relates to the construction of railway cars, more particularly to corrugated sheet metal end structures for railway cars, and one of the principal objects of the invention is to provide a vertically corrugated car end in which the corrugations are formed of a maximum cross sectional area at points above the floor of the car and below the center horizontal line of the end structure, thereby giving the end its greatest strength to resist the thrusts and pressures of the cargo, for example, at the place where strength is particularly required.

The invention has for further objects such other new and improved constructions, arrangements and devices relating to corrugated sheet metal car ends as will be herein-after described and claimed.

The invention is illustrated as embodied in a sheet metal car end for gondola cars. The same principles of construction might be applied to end structures for different types of cars.

In the drawing,

Figure 1 shows, in elevation, the end of a railway car constructed in accordance with my invention.

Fig. 2 is a sectional plan on line 2-2 of Fig. 1, and

Fig. 3 is a vertical sectional view on line 3-3 of Fig. 1.

Like characters of reference designate like parts in the several figures of the drawing.

Referring to the drawing, the under frame of the car is indicated at 10. 11 is the floor ing and 12 the side walls. 13 represents the side stakes. The end of the car, in the embodiment of the invention herein shown, consists preferably of a single sheet of steel 14 formed with a plurality of vertical cor rugations 15. These corrugations are deepest and widest at points above the floor of the car but below the horizontal center line of the end. The corrugations taper toward their extremities and die out within the edges of the sheet. This arrangement gives

the end structure maximum strength along a line where the greatest strength is required. It will be understood that the ends of railway freight cars, of all types, are subjected to thrusts and pressures from the lading due to inertia when the train starts and stops. These thrusts and pressures are greatest in the lower half of the end and are most likely to be destructive when exerted against the end structure along a line above the floor approximately at the place of greatest cross sectional area of the corrugations as shown in the drawing.

To still further strengthen and rigidify the end structure along this line I preferably provide a transverse strip of metal 16 which is riveted to the corrugations at their deepest point, as indicated at 17. The end sheet 14 is preferably formed with flanges 18 which overlap the side walls 12 of the car. Within the car are arranged angle bar corner posts 19 to which the flanges 18 are secured by bolts 20. The body portion of the end sheet may be riveted to the other legs of the angle bars by rivets 21.

The lower edge of the end sheet 14 is provided with means forming a horizontal stiffening and attaching flange. For example, the lower edge of the sheet may be flanged out, as indicated at 22, and riveted or otherwise secured, as at 23, to the under frame of the car. At the upper edge of the sheet is arranged a reinforcing member 24, preferably an angle bar, the vertical leg of which is riveted at 25 to the end sheet. The angle bar is provided preferably with angular extensions or wings 26 secured to the corner posts 21.

This application is a division of my co-pending application Serial No. 799,968, filed November 8, 1913.

I claim:

1. A sheet metal car end structure comprising an end sheet formed with vertical corrugations, the cross sectional areas of which are greatest at points between the horizontal center line of the end and the floor and which taper in width and depth toward their extremities.

2. A sheet metal car end structure comprising an end sheet formed with vertical corrugations terminating within the edges of the sheet, the cross sectional areas of which are greatest at points between the

horizontal center line of the end and the floor and which taper in width and depth toward their extremities, and means providing a horizontal attaching and rigidifying flange at the lower edge of the sheet adapted to be secured to the under frame of the car.

3. A sheet metal car end structure comprising an end sheet formed with vertical 10 corrugations terminating within the edges of the sheet, the cross sectional areas of which are greatest at points between the horizontal center line of the end and the floor and which taper in width and depth 15 toward their extremities, the lower edge of the sheet being bent over to provide a horizontally disposed flange adapted to be attached to the under frame of the car.

4. A sheet metal car end structure comprising an end sheet formed with vertical 20 corrugations, the cross sectional areas of which are greatest at points between the horizontal center line of the end and the floor and which taper in width and depth 25 toward their extremities, and means providing a horizontal rigidifying flange at the upper edge of said sheet adapted to transmit stresses from said corrugations to the side wall of the car.

30 5. A sheet metal car end structure comprising an end sheet formed with vertical corrugations, the cross sectional areas of which are greatest at points between the horizontal center line of the end and the 35 floor and which taper toward their extremities, and an angle bar attached to the upper edge of said sheet adjacent the upper end of said corrugations with its ends secured to the side walls of the car so as to transmit 40 stresses from said corrugations to the side wall structure.

6. A sheet metal car end structure comprising an end sheet formed with vertical corrugations, the cross sectional areas of 45 which are greatest at points between the horizontal center line of the end and the floor and which taper toward their extremities, means providing a horizontal attaching and rigidifying flange adjacent the lower 50 ends of the corrugations adapted to be secured to the under frame of the car, and means providing a horizontal rigidifying flange at the upper edge of the sheet, said rigidifying flanges being adapted to trans- 55 mit stresses from the corrugations to the

underframe and side wall structures of the car, respectively.

7. A sheet metal car end structure comprising an end sheet formed with vertical corrugations, the cross sectional areas of 60 which are greatest at points between the horizontal center line of the end and the floor and which taper in width and depth toward their extremities, the lower edge of the sheet being bent over to provide a horizontally disposed flange adapted to be attached to the under frame of the car, and an angle iron secured to the upper edge of the sheet with its ends attached to the side walls of the car. 70

8. A sheet metal car end structure comprising an end sheet formed with vertical corrugations, the cross sectional areas of which are greatest at points between the horizontal center line of the end and the 75 floor and which taper toward their extremities, and a metal band extending across the end and attached to the corrugations at their places of greatest cross sectional area.

9. A sheet metal car end structure comprising an end sheet formed with vertical corrugations, the cross sectional areas of which are greatest at points between the horizontal center line of the end and the floor and which taper toward their extremities, the vertical edges of the sheet being formed to provide flanges overlapping the side walls of the car, marginal stiffening flanges extending transversely of said corrugations and angular members on the inside of the car attached to said flanges through the side walls of the car and to the body portion of the end sheet. 80 85

10. A sheet metal car end structure comprising an end sheet formed with vertical 90 corrugations, the cross sectional areas of which are greatest at points between the horizontal center line of the end and the floor and which taper toward their extremities, the vertical edges of the sheet being 100 formed to provide flanges overlapping the side walls of the car, marginal stiffening flanges extending transversely of said corrugations and angular members on the inside of the car extending from top to bottom of the side walls, attached to said flanges through the side walls of the car and to the body portion of the end sheet. 105
